UNITED STATES PATENT OFFICE.

ADOLPHUS HENRY ARZT, OF LONDON, ENGLAND.

GAS OR VAPOR BURNER.

SPECIFICATION forming part of Letters Patent No. 763,140, dated June 21, 1904.

Application filed November 18, 1902. Serial No. 131,808. (No model.)

To all whom it may concern:

Be it known that I, ADOLPHUS HENRY ARZT, a citizen of England, residing at 38 Margaret street, Cavendish Square, London, England, 5 have invented certain new and useful Improvements in Gas or Vapor Burners for Heating, of which the following is a specification.

Burners for heating have been made in which the mixing tube or chamber of the 10 well-known Bunsen burner has been partitioned by diaphragms of metal gauze or the like into a number of chambers, the object being to effect a better intermixture of the combustible gas or vapor and air. In such 15 burners the mixture burns on a sheet of metal gauze or a perforated metal plate on the top of the mixing-tube.

My invention relates to improvements in burners of this kind, as I will describe with 20 reference to the accompanying drawings, in which—

Figure 1 is a vertical section of my improved burner. Fig. 2 is a sectional plan of the mixing-tube on line 22 of Fig. 1, and Fig. 25 3 is a plan of the top plate of the burner.

a is the mixing-tube of the burner, which is expanded at its lower end *b* and is riveted to feet *c*. The injector-nozzle *d* discharges gas against the plate *e*, which forms a central disk 30 in a diaphragm *f*, of wire-gauze or of perforated metal or other suitable material. As indicated by the arrows, the gas is reflected by this plate *e* back into the air, which has been drawn into the mixing-tube. The mixture 35 then passes through the diaphragm and up the mixing-tube to the burner proper, passing on its way through a gauze or perforated plate *g*, which prevents the flame from flashing back.

40 The burner proper comprises two concentric cylinders *h* *i*, the inner of which is conveniently made in one piece, with an inverted truncated hollow cone *k* fixed to the top of the mixing-tube. The outer of the concentric 45 cylinders has fixed to it a cover *l*, which is supported on the inner cylinder by distance-pieces in such manner that the gas passing up the inner cylinder may pass down between the cylinders and up along the sides of the 50 truncated cone *k*, as indicated by the arrows.

Between the upper edge of the cone and the cover *l* of the outer cylinder is an annular opening at which the mixture of gases burns. On the said cover *l* I place a ring *m*, coned outwardly in an upward direction, which I 55 fill with sand or other material capable of being heated to a high temperature and of thus improving the radiation of the burner, and as a flame-spreader I cover this ring with a plate *n*, having a scalloped edge. 60

Having thus described the nature of my said invention and the best means I know of carrying the same into practical effect, I claim—

1. A gas or vapor burner for heating having a mixing-tube, an injector-nozzle, a plate 65 above the nozzle in a position for the gas issuing from the nozzle to impinge upon it, a perforated diaphragm in a position for the gas to pass therethrough immediately after it has impinged upon the said plate, two concentric 70 cylinders on the top of the said mixing-tube, the inner cylinder being combined with an inverted truncated hollow cone and the outer cylinder having a fixed cover supported on the inner cylinder by distance-pieces, substan- 75 tially as described.

2. A gas or vapor burner having a mixing-tube, two concentric cylinders on the top thereof, the inner cylinder being combined with an inverted truncated hollow cone and 80 the outer cylinder having a fixed cover supported on the inner cylinder by distance-pieces, an inverted conical ring on the cover of the said outer cylinder holding refractory material, and a flame-spreading plate covering the said ring, substantially as described. 85

3. A gas or vapor burner for heating having a mixing-tube, an injector-nozzle, a plate above the nozzle in a position for the gas issuing from the nozzle to impinge upon it, a perforated diaphragm in a position for the gas to pass therethrough immediately after it has impinged upon the said plate, two concentric cylinders on the top of the said mixing-tube, the inner cylinder being combined with an 95 inverted truncated hollow cone and the outer cylinder having a fixed cover supported on the inner cylinder by distance-pieces, an inverted conical ring on the cover of the said outer cylinder holding refractory material, 100

and a flame-spreading plate covering the said ring, substantially as described.

4. A gas or vapor burner having a mixing-tube, a dash-plate near the lower end thereof, 5 concentric tubes or cylinders at the top of said tube, a passage between the cylinders communicating with an upwardly-flaring passage into which the gas enters from the cylinders, and a cover extending over the cylinders; substantially as described.

5. A gas or vapor burner having a mixing-tube, a dash-plate near the lower end of said

tube, a perforated diaphragm separating the mixing-tube from the burner, an upwardly-extending flaring gas-passage, and a flaring 15 disk above said passage and containing refractory material; substantially as described.

In testimony whereof I have hereunto set my hand in presence of two subscribing witnesses.

A. HENRY ARZT.
